UNITED STATES PATENT OFFICE.

JAMES A. ELLIOTT, OF SYCAMORE, ILLINOIS.

BROODER.

1,072,217.

Specification of Letters Patent.

Patented Sept. 2, 1913.

Application filed March 8, 1913. Serial No. 752,849.

To all whom it may concern:

Be it known that I, JAMES A. ELLIOTT, a citizen of the United States, residing at Sycamore, in the county of Dekalb and State of Illinois, have invented new and useful Improvements in Brooders, of which the following is a specification.

This invention relates to brooders or brooding coops, and it has for its object to produce a simple, inexpensive and efficient device of the class specified for raising incubator chicks.

A further object of the invention is to produce a device of the class described including a body structure and a revoluble door structure, the latter including doors or closures of different kinds, such as a screen door, a slat door and a solid door, any one of which may be presented in registry with a door aperture in the body structure.

A further object of the invention is to produce a device of the class described which shall be vermin-proof and sanitary, which may be easily maintained in a clean and sanitary condition, and which shall have no corners that the chicks may crowd into.

A further object of the invention is to produce a simple and efficient device of the character described, which, in addition to the features enumerated, shall be provided with a removable lid or cover through which access may be had to the interior.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings, —Figure 1 is a side elevation of the body structure with the removable door structure detached. Fig. 2 is a perspective view, showing the revoluble door structure detached. Fig. 3 is a vertical sectional view of the complete device. Fig. 4 is a horizontal sectional view taken on the line 4—4 in Fig. 3.

Corresponding parts in the several figures are denoted by like characters of reference. The body structure of the improved device consists of a sheet metal vessel A having a cylindrical wall 5 and a flat bottom 6 surrounded by a bead 7. The cylindrical wall 5 is provided near its upper edge with a circumferential bead 8. A conical lid or cover 9 is provided, said lid having an annular flange 10 which is provided with bayonet slots 11 to engage pins or studs 12 that project from the wall 5 of the vessel A above the flange 8, for the purpose of assembling the lid with the body of the vessel. Said lid is provided with a handle 13, whereby the device may be carried, and the lid is provided at the apex of its conical portion with a ventilating flue 14 protected by a conical cap 15 and having ventilating apertures 16. The wall 5 of the body portion is provided with a door opening 17.

A door structure is provided which consists of a strip 18 of sheet metal or other suitable material, said strip being provided along its upper and lower edges with bands 19 or straps 19 of hoop iron or other similar material. The strip 18, together with the straps 19, is bent into an approximately cylindrical form, and the straps or bands 19 are provided with terminal outstanding lugs 20 which are apertured for the passage of connecting members, such as bolts 21 having nuts 22, whereby the ends of the straps are connected together to form a substantially cylindrical structure, as clearly seen in Fig. 2. The straps 19, however, are of greater length than the strip 18 so that a vacant space will occur between the end edges of said strip. The hoops or bands 19 are of such length as to fit around the cylindrical wall 5 of the body structure, the parts being so proportioned that by tightening the nuts 22 on the bolt 21, the door structure, which rests on the bead or flange 7, may be secured in any position to which it may be adjusted.

It will be seen that by loosening the nuts 22, the door structure may be rotated about its axis and that of the body structure A so as to place the open space between the end edges of the strip 18 in registry with the door aperture 17 in the wall 5 of said body structure. The strip 18, moreover, is provided with apertures 23 and 24, which are partly obstructed, respectively, by a

screen 25 and by slats 26. Either of these apertures may be placed in registry with the apertures 17, which latter will thus be partly obstructed either by the screen 25 which will prevent the passage of chicks or by the slats 26 which may be spaced apart to permit small chicks to pass while larger fowls will be excluded. The strip 18 also has a solid portion which when placed in registry with the aperture 17 will entirely obstruct the latter. As previously stated, the door structure may be secured in adjusted position by simply tightening the nuts 22.

The body structure A may be interiorly 15 lined or protected against cold in any suitable and well known manner which, however, is no part of the present invention.

It will readily be seen that I have provided a simple and inexpensive brooding 20 coop which is particularly convenient and useful in that by simply removing the lid, access may be had to the interior at any time, while by adjusting the revoluble door structure provision may be made for the free 25 or the limited entrance and exit of chicks, or the admission and exit of the chicks may be obstructed with or without interfering with the ventilation. The entire coop with 30 contents may be conveniently carried by the handle 13. The body portion of the coop being in the nature of an ordinary cylindrical sheet metal vessel may be very easily maintained in an absolutely clean and sanitary condition. It is also evident that 35 the improved device may be conveniently made in different sizes, and that different sizes may be nested together for transportation.

Having thus described the invention, what 40 is claimed as new, is:—

1. A brooding coop comprising a cylin-

drical vessel, the wall of which has a door aperture, in combination with a revoluble door structure including a hoop-shaped band having terminal lugs, and means 45 whereby said lugs are adjustably connected together.

2. A brooding coop comprising a cylindrical vessel having a flat bottom surrounded by a bead, in combination with a cylindrical door structure supported on said bead, and means whereby said door structure may be tightened about the wall of the body structure to retain it frictionally against displacement. 50

3. A brooding coop comprising a cylindrical vessel constituting a body structure and having a door aperture in the wall thereof, in combination with a cylindrical door structure surrounding the wall of the 60 body structure and having solid and apertured portions, the latter being partially obstructed, and means whereby the door structure may be tightened about the wall of the body structure to retain it frictionally 65 against displacement.

4. A brooding coop comprising a cylindrical vessel, the wall of which has a door opening, a lid detachably connected with the vessel and having a ventilator, and a door 70 structure surrounding the wall of the body structure and supported for rotation about its axis, and means whereby said door structure may be tightened about the wall of the body structure to maintain it frictionally 75 against displacement.

In testimony whereof I affix my signature in presence of two witnesses.

JAMES A. ELLIOTT.
